ANTONIO F. SMITH, OF ELLSWORTH, MAINE.

Letters Patent No. 70,087, dated October 22, 1867.

IMPROVEMENT IN VENTILATORS.

The Schedule referred to in these Letters Patent and making part of the same.

TO ALL PERSONS TO WHOM THESE PRESENTS SHALL COME:

Be it known that I, ANTONIO F. SMITH, of Ellsworth, in the county of Hancock, and State of Maine, have invented a new and useful Ventilator and Spark-Annihilator for the smoke-discharge pipe of a stove; and I do hereby declare the same to be fully described in the following specification, and represented in the accompanying drawings, of which—

Figure 1 is a side elevation,

Figure 2 a longitudinal and vertical section,

Figure 3 a horizontal section, and

Figure 4 a transverse section of it.

In such drawings, A denotes an elongated box, having a partition, B, extending across and within it near its top. It also has another partition, C, carried across it below the partition B, and at a short distance from one end of the box, and down to the bottom of the box. Both partitions are foraminous, or are perforated with holes *a a a, b b b*. An induction pipe, D, leads up through the bottom of the box, and to and opens through the partition B. Furthermore, an eduction pipe, E, leads out of one end of the box, and there are two or any other suitable number of air-conduits F, leading lengthwise through the box and into the escape pipe E; each pipe F opening through the rear end of the box, in order that air from the atmosphere surrounding the box may enter and pass through the pipe or pipes F and into the escape pipe or flue E. Over the upper end of the pipe D, and attached to the top of the box A, is a concavo-convex deflector G.

The apparatus so made is intended to be applied to the smoke-discharge flue of a stove, in such manner as to cause the smoke from the stove to pass up through the pipe D, and into the space H over the partition B, thence through the holes *a a b b, &c.*, of the two partitions B C, and thence into the pipe E, the deflector G serving to deflect and distribute the smoke upon the partition B. The pipes F when heated by the smoke will cause currents of air to escape from the apartment in which the stove may be, and thus the room will be ventilated of bad air. The soot and carbonaceous matters in the smoke will be intercepted by and consumed within the box A, where they will operate to heat such box, and thereby aid in heating the air surrounding it. In making the application, the escape pipe of the stove is to be led into the pipe D, and the pipe F is to conduct the smoke to the chimney. Under these circumstances the smoke discharged from the stove will, before passing into the chimney, be caused to flow through the apparatus.

I claim the said ventilator and spark-annihilator, made substantially as described, viz., of the box A, the induction and eduction smoke pipes D E, the perforated partitions B C, and the ventilating pipe or pipes E, or with the same and the deflector G arranged as specified.

ANTONIO F. SMITH.
